APPLIANCE FOR EMBALMING

Howard B. Cox, Akron, Ohio

Application June 1, 1949, Serial No. 96,502

3 Claims. (Cl. 27—24)

1

This invention relates to an appliance for embalming, in which an efficient cutter bar is employed in a trocar and a drainage tube.

An object of this invention is to provide an embalming apparatus with a drainage tube, which is inserted in the vein of a dead human body to conduct therefrom blood displaced by embalming fluid injected under pressure in the arteries.

Another object of this invention is to facilitate the removal of blood clots, chicken-fat clots, etc., by the scissor-action of a cutter bar which operates within the drainage tube.

Another object of this invention is the improvement of the trocars, which are inserted into the abdominal and thoracic cavities of the dead human body to aspirate liquids, gases, and unexcreted waste materials from the internal organs. It is also used to inject preservative chemicals under pressure into the abdominal and thoracic cavities to preserve those organs not reached by preservative chemicals during the arterial injection.

A still further object of this invention is to provide a compact and conveniently operated trocar, having certain advantageous features.

With the foregoing and other objects in view, this invention comprises certain novel constructions, combinations and arrangements of parts as will be hereinafter fully described, illustrated in the accompanying drawings, and more particularly pointed out in the appended claims.

In the drawings:

Figure 1 is a longitudinal, vertical, sectional view of a trocar, showing my invention.

Figure 2 is an enlarged, vertical, sectional view of the trocar, with the cutter bar shown in elevation.

Figure 3 is an enlarged, transverse, sectional view, taken on line 3—3, Fig. 1.

Figure 4 is a vertical, longitudinal, sectional view of a drainage tube, showing the cutter bar in elevation, in accordance with this invention.

Figure 5 is an enlarged, fragmentary, sectional view of the drainage tube, showing the cutter bar in elevation.

Figure 6 is an enlarged, transverse, sectional view, taken on line 6—6, Fig. 4.

Referring to the drawings in which Figs. 1 to 3 show the preferred specie of this invention, 1 designates a sectional tube in which is positioned a cutter bar 2. This cutter bar 2 is provided with two longitudinal grooves 3, Fig. 3, that produce four blades 4. These blades 4 are ground to a razor sharpness. At the point end 5 the cutter bar 2 is tapered as shown and is seated in the

2

cavity of the puncture-point tip 6. This tip 6 is tapered to facilitate puncturing the cavity and organs contained therein. In the tip 6 is an aperture 7. This aperture 7 allows fluids to escape to prevent the collection of fluids that might disrupt the accuracy of the cutter bar 2. The detachable section 8 of the tube is also provided with preferably two apertures 9. It is obvious that the section 8 is screw-threaded into the main part of tube 1. This section 8 constitutes a part of the tube 1. The main part of tube 1 is provided with a plurality of apertures 10. It will be noted that these apertures 10, as well as apertures 9, are near the point end of the tube 1.

On one end of the tube 1 is screwed the handle 11. An escape aperture 12 is formed on tube 1 near the handle 11 and over this aperture is placed a hose attachment 13. This aperture 12 is for aspirated materials to pass through.

The cap 14 is threaded onto the handle 11 to lock the cutter bar 2 in the tube 1 when retracted by pulling back on knurled knob 15, which is attached to the plunger rod 16, the plunger rod being secured to the inner end of the cutter bar 2.

The hose attachment 13 may be attached to a length of rubber hose (not shown), through which suction or aspiration pressure is applied. This pressure withdraws waste materials, through the trocar, from the cavities.

Upon inserting the trocar through the abdominal wall, aspiration of waste materials commences. In this invention the cutter bar 2, with its four blades 4, rotates within the tube 1, and across said holes or apertures 9 and 10 by turning the knurled knob 15 either clockwise or counter-clockwise. By turning the knurled knob 15, the plunger rod 16 also turns, which rotates the cutter bar 2. This action allows the sharp blades 4 to pass over the apertures 9 and 10, simulating a scissor-like action which slices the clogging material into small pieces that can then enter into the longitudinal grooves 3 in the cutter bar 2, then pass through tube 1, aperture 12 and into hose attachment 13.

The cutter bar of this invention eliminates this removal and allows easy, uninterrupted aspirating and injection of preservative chemicals without removing to clean. Further, the cutter bar trocar is designed to be adapted to both adult and baby size trocars.

In the embodiment shown in Figures 4 to 6, the tube 1a, that is open at its outer end, and which is adapted to be inserted in a vein, has numerous apertures 10a. These apertures 10a

are provided for the entrance of clots. Three-fourths of the way back from the outer end of tube 1a is located an aperture 12, over which is placed the hose attachment 13, similar in construction to the embodiment shown in Figure 1. The inside diameter of the tube 1a is of smaller diameter at 1b. The enlargement 1c in the diameter of the tube extends to the knurled knob 15, for the purpose hereinafter described.

The outer end of the cutter bar 2a extends beyond the tube 1a so as to provide a director for the tube when inserted into the vein. In this embodiment a broach 16a is formed at the inner end of the cutter bar 2a. This broach 16a fits the inner diameter of the tube 1a like a piston fits a cylinder, to provide a means for shutting off the drain tube when drainage is not desired. The plunger rod 16 is connected at one end to the broach portion of the cutter bar and at its other end is connected to the knurled knob 15.

When this drainage tube is inserted into the vein, the cutter bar is in a closed position, with the outer projecting end as shown. This projecting end aids insertion into the vein. To facilitate drainage, knurled knob 15 is drawn back, which results in pulling the cutter bar into the area of greatest inside diameter of the tube, indicated by 1c. The greatest diameter 1c allows compressed air pressure and fluids to escape around the broach 16a and out of the aperture 12 into the hose attachment 13.

When the tube is in the drainage position, blood is displaced by embalming fluid, under pressure, in the arteries, and out through the tube. When clots are too large to be drained and plug up apertures 10a, the cutter bar is returned to the closed position, Fig. 4, and turned on its axis within the tube by twisting the knurled knob 15. The sharp cutting blades 4 create a scissor-action across the apertures 10a and cut off these clots in small pieces, which can be drained. The knurled knob 15 can be rotated clockwise or counter-clockwise to turn the cutter bar either way. Then the knurled knob 15 is drawn back to place the tube in an open position. The broach 16a causes a suction action and aids in drawing the small cut up clots through the tube 1a and out through the aperture 12 and hose attachment 13.

The broach 16a also serves to hold tube 1a in a closed position when injection without drainage is desired.

The cutter bar is so attached that easy removal for sharpening is possible, making the life of the tube greatly increased. The apparatus herein described is designed to be adapted as a jugular, axillary, and femoral drainage tube.

In the two embodiments of this invention, the cutter bar is substantially the same in construction, involving the four razor-like blades 4, associated broadly in an apertured tube, as hereinbefore described.

While I have described the preferred embodiments of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In an apparatus of the class described, the combination of a cylindrical tube provided with apertures, an elongated cutter bar mounted for rotation in said tube and of substantially I-shape in cross section, the end surfaces of the section being arcuate in form and fitting closely in said tube, said section including a web portion extending centrally between the section ends, the arcuate end surfaces and the sides of the web being joined by surfaces diverging from the sides of the web and meeting said end surfaces at acute angles to form sharp knife edges adapted to work across said apertures, and manually operated means connected to said cutter bar for imparting rotative movement thereto.

2. In an apparatus of the class described, the combination of a cylindrical tube provided with a pointed end, said tube provided with apertures in its side and with a transverse aperture in said pointed end, a rotatable cutter bar in said tube and being adapted to register with said apertures, said cutter bar being of substantially I-shape in cross section, the end surfaces of the section being arcuate in form and fitting closely in said tube, said section including a web portion extending centrally between the section ends, the arcuate end surfaces and the sides of the web being joined by surfaces diverging from the sides of the web and meeting said end surfaces at acute angles to form sharp knife edges, a plunger rod connected at one end to said cutter bar, and a knob on an end of said plunger rod.

3. In an apparatus of the class described, the combination of a cylindrical tube, said tube provided with apertures, a detachable section on said tube, said section provided with apertures in its side and with a transverse aperture near its outer end, a threaded handle on the inner end of said tube, a cap threaded on one end of said handle, a hose attachment on said tube, a rotatable cutter bar of substantially I-shape in cross section, the end surfaces of the section being arcuate in form and fitting closely in said tube, said section including a web portion extending centrally between the section ends, the arcuate end surfaces and the sides of the web being joined by surfaces diverging from the sides of the web and meeting said end surfaces at acute angles to form sharp knife edges, a plunger rod extending through the threaded cap on said handle and connected to said cutter bar, and a knob on the outer end of said plunger rod.

HOWARD B. COX.
